UNITED STATES PATENT OFFICE

138,548

DESIGN FOR A COMBINED PISTON AND COMPRESSION HEAD OR SIMILAR AR- TICLE

Charles A. Toce and Victor J. Toce, Houston, Tex.,
assignors to Federal Aircraft Engine Corpora-
tion, Houston, Tex.

Application April 13, 1942, Serial No. 106,569

Term of patent 14 years

(Cl. D46—1)

To all whom it may concern:

Be it known that we, Charles A. Toce and Victor J. Toce, citizens of the United States, residing at Houston, in the county of Harris and State of Texas, have invented a new, original, and ornamental Design for Combined Piston and Compression Head or Similar Article, of which the following is a specification, reference being had to the accompanying drawing, forming part thereof.

Fig. 1 is a side elevational view of a combined

piston and compression head or similar article, showing our new design;

Fig. 2 is a front elevational view; and
Fig. 3 is a bottom plan view thereof.

We claim:

The ornamental design for a combined piston and compression head or similar article, as shown.

CHARLES A. TOCE.
VICTOR J. TOCE.
